UNITED STATES PATENT OFFICE.

BENJAMIN HOLMES, OF PHILADELPHIA, PENNSYLVANIA, ASSIGNOR TO MORRELL MILLS, INC., OF PHILADELPHIA, PENNSYLVANIA, A CORPORATION OF PENNSYLVANIA.

DESIGN FOR A TEXTILE FABRIC.

Application filed January 21, 1927. Serial No. 20,449. Term of patent 3½ years.

To all whom it may concern:

Be it known that I, BENJAMIN HOLMES, a citizen of the United States, residing in the city and county of Philadelphia, State of Pennsylvania, have invented the new, original and ornamental Design for a Textile Fabric, of which the following is a specification, reference being had to the accompanying drawing, forming part thereof.

The figure is a plan view of a textile fabric showing my new and ornamental design.

I claim:

The ornamental design for a textile fabric as shown.

BENJAMIN HOLMES.
